SHEET OF DISPLAY LETTERS FOR FORMING SIGNS OR THE LIKE

Richard W. Conner, 20 Cedar St.,
Millville, N.J. 08332

Filed Apr. 14, 1967, Ser. No. 6,699

Term of patent 14 years

(Cl. D64—12)

The figure on the drawing is a top plan view of a sheet of display letters for forming signs showing my new design, the sheet being plain on the back and of conventional thickness.

I claim:

The ornamental design for a sheet of display letters for forming signs or the like, substantially as shown and described.
